UNITED STATES PATENT OFFICE.

HEINRICH ACKERMAN, OF BERLIN, GERMANY.

SPRING-MATTRESS.

No. 926,375.

Specification of Letters Patent. Patented June 29, 1909.

Application filed November 12, 1908. Serial No. 462,201.

To all whom it may concern:

Be it known that I, HEINRICH ACKERMANN, a subject of the King of Prussia, and resident of 43-44 Warschauerstrasse, Berlin, German Empire, have invented certain new and useful Improvements in Spring-Mattresses, of which the following is a specification.

This invention relates to spring mattresses and its object is to provide a form of mattress which shall be durable and in which the cover employed will not have a tendency to fold or collect dust and become easily torn.

According to the present invention the springs are arranged between two frames and tend to press these frames apart, but the frames are held resiliently together by means of further springs which tend to compress the main springs.

The invention is illustrated in several modifications in the accompanying drawings, in which:

Figure 1 is a side view of the mattress, Fig. 2 is a plan, Fig. 3 is a detail view of the method of joining the springs to the frame parts, Fig. 4 is a plan of the arrangement shown in Fig. 3, Fig. 5 shows a slightly modified arrangement. Fig. 6 shows a form of hooked link for employment between the springs. Fig. 7 is a sectional perspective view showing the mattress with covering thereon. The upholstery or padding is in this form provided on both sides. Fig. 8 shows another form of mattress in which the upholstery is provided on one side only. Fig. 9 is a front view. Fig. 10 is a sectional elevation of a modified form of holding arrangement for the covering. Fig. 11 is a perspective view of this modified holding arrangement.

In carrying the invention into effect according to the form shown the frames are composed of rigid rods 4 which are bent inwardly in their center portions as seen in the upper part of Fig. 1. The rods 4 form a rectangular rigid frame in which the center portions of the sides lie in a different plane to the corners. The opposite frame in Fig. 1 is shown as flat and composed of plain rods 5. To the raised corner parts of the upper frame there are fixed links 1 which are fastened to springs 2 whereby the opposite raised corners of the upper frame are connected by spring cords. Between the two rigid frames there are arranged springs 3 which tend to press the two rigid frames apart; these

springs 3 are articulated to one another at their upper and lower ends by means of hooks 7 which are shown in enlarged detail in Fig. 6. In addition to the springs 3 there are also provided springs 6 by which the frames are drawn toward one another. The connecting hooked legs shown in Fig. 6 are bent at their ends so that the tension acts on the hook directly in the line of the central rod part and therefore there is no tendency for the hooked end to be bent or disfigured when in use. Inclined hooks 1^a are arranged for the corner and exterior springs. These hooks are preferably crossed as shown at 1^a and 1^b. The positions in which the pairs of crossed hooks are arranged can be seen from the double lines in the plan of Fig. 2. The lower side of the frame is provided with cross steel bands 8 shown in Figs. 3 and 4 and the springs are fastened to these bands at their foot in the manner illustrated in detail in these figures.

The springs 3 pass through eyes formed half in the band springs 8 and half in small tongues 9. These tongues are stamped from the bands 8 and held by means of metal bands 10 which grip in the bands 8 by passing through holes therein and being turned over at 10^a. Instead however of fixing the springs to the bands 8 in the manner shown in Figs. 3 and 4 these springs may be fixed by inverted U-bands 11, as shown in Fig. 5. These bands are simply passed through holes in the bands 8 and then their ends turned over as shown.

In consequence of the arrangement above described the mattress will always retain its shape even when in use for some considerable time, owing to the fact that the springs 3 are resiliently held in compression by means of the tensioning springs 6. Also when the springs 3 become deformed through time this deformity does not produce any marked defect in the mattress as the tension springs 6 still retain the mattress tight. Further by the insertion of the springs 6 the cloth covering of the mattress is much better kept and all folding prevented. By suitably shaping the frames so that the bent in parts lie nearer or more remote from the opposite frame the amount of compression to which the springs 3 may be subjected may be limited.

Instead of arranging only one of the frames with bent-in center parts, as shown at the upper part of Fig. 1 both frames may

be arranged as shown in Fig. 7. In this figure also the mattress is shown as provided with a covering which avoids all ingress of dust. The lower part of the mattress as well as the upper part in this form is provided with a covering or padding of horse-hair or the like 13. Over this padding there is laid a layer of cloth 14 which is sewn to the bottom layer of cloth 12 at 15. The upper and bottom layers 14 and 12 are also connected by means of diagonally arranged cross stitches 16. Over the padding produced as described there is passed a covering 17 which is sewn to the bottom layer 12 at 15 the edges. At the point where the two edges meet they are bound by means of lacing 18 which engages in holes 19. In addition to the holes 19 additional holes 20 are provided in each of the parts to be placed together so as to allow of these parts being more tightly drawn. In this way all folds may be avoided, which would be caused by long protracted and severe use. The lacing 18 and 19 is only provided at one side of the mattress while the other side that is the left hand side of Fig. 7, is sewn together. Over the mattress covering formed in this way a further covering 21 is provided which is sewn at the side which passes over the lacing 18 and is laced at the opposite side in the same manner as the inner covering; in this way all ingress of dust is avoided.

In Fig. 8 the parts are arranged as described above with the exception that only the upper part of the mattress is covered with padding. The form shown in Fig. 8 therefore may only be used on one side, whereas the form shown in Fig. 7 may be used on both sides.

Instead of the lacing described the coverings for the mattress may be fixed by means of the spring catch shown in Figs. 9-11. In this form of device there is provided a backing plate 22 having two lugs 23 which support a pivot 24. To this pivot there is fixed a plate 25 having a short gripping part 26 provided with teeth to catch the cloth in the manner well known in garment-suspenders. The plate 22 is also provided with pins 31 which are adapted to grip in eyes 30 provided on the covering. The arrangement of the joints may be as described with reference to Figs. 7 and 8.

The fixing 31 may be provided with a press button such as is used in gloves and the like.

I claim:

1. A spring mattress for beds and the like having in combination with a covering, two rigid frames relatively movable toward and away from one another, sets of springs tending to press said frames apart, further springs tending to draw said frames together and hold said first mentioned springs in compression.

2. A spring mattress for beds and the like having in combination with a covering, two rigid frames, said frames having side rods with their center parts inwardly bent with respect to the outer surface of the mattress, springs tending to press said frames apart and further springs tending to draw said frames toward one another and hold said first mentioned springs in compression.

3. A spring mattress for beds and the like having in combination with a covering, two rigid frames, said frames being composed of side rods with their center parts inwardly bent and placed with the inwardly bent portions toward one another so that the corners of said frames lie in a plane other than their center portions, springs articulated together and onto said rigid frames and tending to press said frames apart, and additional springs fixed to said frames and tending to draw the same together and compress said first mentioned springs.

4. In combination with a spring mattress, a covering comprising a cloth covering arranged in halves, one half being sewn at one of its longitudinal edges to the other half, and the opposite edges of said halves being provided with sets of eyes arranged in rows at different distances from the edges and a cord adapted to engage with one or other of the rows of eyes in each of said edges, substantially as described.

5. In combination with a spring mattress, a covering comprising a cloth covering arranged in halves, one half being sewn at one of its longitudinal edges to the other half, and the opposite edges of said halves being provided with sets of eyes arranged in rows at different distances from the edges and a cord adapted to engage with one or other of the rows of eyes in each of said edges, an additional covering composed of two parts sewn together at one edge, said sewn joint being placed over the laced joint and laced together at the other end.

6. In combination with a spring mattress, a covering comprising an inner cover composed of two covering parts sewn together at one pair of the joining edges, and means for detachably fastening the opposite edges and an outer covering placed over said inner cover and comprising two parts sewn together at one pair of their joining edges, said sewn joint being placed over the detachable joint of the inner cover and means for detachably joining the other pair of joining edges of said outer cover.

In witness whereof I have hereunto set my hand in the presence of two witnesses.

HEINRICH ACKERMANN.
